TELEVISION TRANSMITTING SYSTEM

Richard L. Campbell, Hasbrouck Heights, N. J.,
assignor to Allen B. Du Mont Laboratories, Inc.,
Passaic, N. J., a corporation of Delaware

Application May 9, 1939, Serial No. 272,612

2 Claims. (Cl. 178—7.2)

My invention relates to improvements in television transmitting systems, and more particularly to those employing a cathode-ray tube for generating the video or picture signals.

In the operation of television transmitters of the character referred to, undesirable surges, tending to overload the video amplifier, are developed during the vertical return-line periods and the horizontal return-line periods. Also, in the transmission of motion-picture film, the shutter action is accompanied by development of an intense surge which might overload the video amplifier. A blanking circuit is therefore necessary in the early stages of the amplifier to prevent overload of succeeding stages by these surges. The blanking pulses must be of sufficient amplitude to neutralize the surge pulses from the transmitter cathode-ray tube. Heretofore, these surges have been blanked out by using a saturated tube in an early stage of the amplifier. With this arrangement, however, the amplifier did not have the desired linear characteristic.

With the foregoing in mind, it is an object of my invention to provide an improved television transmitting system of the character referred to in which the so-called blanking can be effected without recourse to a saturated tube, and in which the video amplifier may be designed with more linear characteristics.

Other objects and advantages will hereinafter appear.

For the purpose of illustrating my invention, an embodiment thereof is shown in the drawings, wherein—

Figure 1 is a simplified, block diagram of a television transmitting system constructed and operating in accordance with my invention; and

Fig. 2 is an enlarged, simplified, diagrammatic view showing details of the apparatus and circuits in Fig. 1.

In Fig. 1, the reference numeral 10 designates a cathode-ray tube of a conventional construction for generating the video signals, and associated with which are the usual deflecting circuits 11 and 12 for the horizontal and vertical sweeps, respectively. The video signals, amplified by a first amplifier 13, a second amplifier 14, and a line amplifier 15, are fed to a radio transmitter.

The deflecting circuits 11 and 12 are controlled and held locked in step by synchronizing signals supplied from a generator 16 which also generates blanking pulses taken off by the output line 17 and which occur during the vertical return-line and the horizontal return-line periods. The

synchronizing signals are fed for transmission to the line amplifier 15 by a connection 18.

The amplifier 13 comprises the tubes 19, 20, 21 and 22, and associated with these tubes on the

5 same chassis are the tubes 23 and 24. The video signals generated in the transmitter tube 10 are amplified in the two stages 19 and 20 of video amplification and fed to the grid of tube 21. The tube 24 is connected to the plate circuit of tube 21 by means of a coupling resistor 25. The signal at 26 is then impressed upon the tube 22 which has a cathode output circuit, as shown, connected to the video amplifier 14 by connection 27.

10 The signal from connection 27 is fed to the grid 28 of tube 24 by a connection 29, through a condenser 30.

The tube 24 has a common cathode resistor 31 with tube 23 which is operated under such 20 conditions that the current drawn by tube 23 is sufficient to bias tube 24 beyond cut-off when no signal is impressed on the grid 32 of tube 23.

In operation, when the negative blanking pulses represented at 33 are impressed on the 25 grid 32 to cut off tube 23, the excessive bias is removed from the tube 24 to permit the same to draw current, so that for the duration of any blanking pulse, tube 24 functions as a negative feed-back device, which reduces the signal output by virtue of this degenerative connection or circuit. Thus, the signal, generated by injecting the blanking pulses into the video amplifier chain, does not overload the amplifier or cause saturation, such as would be the case if there 30 were no provisions for degenerating this signal, as there are in my improved system.

The arrangement shown has feed-back action over only one stage, but greater feed-back action could be obtained by feeding back over three 40 stages. In such case, instead of making connection to point 26 from the output circuit of tube 24, the connection would be made to the point 34.

It will be understood that modifications, within the conception of those skilled in the art, are 45 possible without departing from the spirit of my invention or the scope of the claims.

I claim as my invention:

1. In a television transmitting system, a cathode-ray tube for generating video signals, an 50 amplifier for said signals, a source of blanking pulses occurring during periods non-effective for the generation of the video signals, a degenerative circuit supplied from a stage of said amplifier and comprising an electron tube, a feed-back connection from the output circuit of said

electron tube to the input circuit of a stage of said amplifier, and an electron tube supplied with said blanking pulses and connected to said first-named electron tube and being operable, in the absence of the blanking pulses, to apply a cut-off bias on said first-named electron tube, said second-named electron tube being itself biased to cut-off by and only during occurrence of said blanking pulses whereby said first-named electron tube draws current for the feed-back action only during occurrence of said blanking pulses.

2. In a television transmitting system, a cath-

ode-ray tube for generating video signals, an amplifier for said signals, a source of blanking pulses occurring during periods non-effective for the generation of the video signals, a first electron tube supplied by and biased to cut-off by said blanking pulses, and a degenerative feed-back circuit from an output circuit to an input circuit of said amplifier, said degenerative circuit comprising a second electron tube controlled by said first electron tube.
